M. E. NORTHROP

BEDPAN

Filed June 24, 1925

FIG. 1

FIG. 2

MABEL E. NORTHROP,
Inventor

per
Oliver D. Barnum,
Attorney

UNITED STATES PATENT OFFICE.

MABEL E. NORTHROP, OF PASADENA, CALIFORNIA.

BEDPAN.

Application filed June 24, 1925. Serial No. 39,263.

My invention pertains to bed pans for the use of invalids, that may be equally serviceable with ordinary home equipment or that of a modern hospital.

Its objects are to provide a pan with comparatively wide bearing surfaces conforming as far as possible to average anatomical lines; to avoid sharp edges or projections which might cause pressure on nerve trunks or blood vessels; to provide a bearing surface for contact with the inner aspect of the thighs while slightly separating the same; to afford comparatively easy access to the anal and vaginal orifices while avoiding possibility of soiling the bed fittings because of forceful evacuations; and to seal against leakage of medicinal applications or pan contents under the back of the invalid.

These objects, among others, are attained by the improved bed pan illustrated in the accompanying drawings, the novelty and utility thereof being made apparent from reading of the same in connection with the accompanying description and explanation.

25 In the drawings

Figure 1 is a perspective side view of the complete invention.

Figure 2 is a front perspective of the improved pan with its detachable apron removed.

Similar numerals indicate similar parts throughout the drawings.

Referring more particularly to the drawings:

1 indicates the main body or receptacle and 5 the opening thereto.

2 indicates the edges of opening 5 turned outwardly for approximately the entire boundaries of opening 5 to form bearing or supporting surfaces for the patient, said bearing surface or flange being prolonged at its lower edge into lip 2^a, adapted to project slightly beyond the body 1.

3 indicates a groove provided in lip 2^a, transversely thereto, adapted to contain a tubular cushion to prevent leakage under the back of the invalid.

4 indicates a detachable apron to serve as an extension of lip 2^a.

5 indicates the opening into the body of the pan 1, approximately oblong in contour, slightly wider at the base and terminating at the crest of horn 7.

6—6 indicate hinges for attachment of apron 4 to lip 2^a by means of perforations 6^a.

7 indicates an upwardly extending projection of the back of body 1, its forward aspect concave and rear convex.

Line X—Y indicates the general direction of the boundaries of opening 5, the same being a rise rearwardly of approximately 30 degrees from the horizontal.

It will be noted that lip 2^a is continuous with flanges 2—2, and that their bearing surfaces rise from the forward or lower margin of said lip 2 on a curved incline toward horn 7, said curve being adapted to conform with the anatomical lines of a patient when in supine position, the general direction being approximately 30 degrees from the horizontal as shown by line X—Y.

Lip 2^a is adapted to support the lower end of the spine and sacral region, and the side flanges in their lower section support the buttocks. The thighs rest on the uprising flanges 2—2 and the inner aspect of the thighs come into contact with said flanges at the approximate junction of said flanges with horn 7.

The general direction and curve of said lip 2^a and flanges 2—2 may be continued forwardly to support the back of the patient by attaching apron 4 by means of hinges 6—6.

The function of horn 7 is twofold; to prevent soiling of the bedding by forceful evacuations, and to slightly separate the thighs for purposes of manipulation and administration. Its concavity affords easy access for the hand or instrument as required.

The function of groove 3 is also twofold. It serves to contain a resilient roll of gauze or tubular rubber packing which will, because of its resiliency, conform to the back of the patient and thus bear a part of the weight; and also constitutes a seal against leakage or seepage of administration fluid or pan contents forwardly to soil the bedding, with its consequent great discomfort to the patient.

In actual operation the pan, with or without apron 4, may be placed in position upon an ordinary mattress in the home, or may be used with special mattresses or bed structure of hospital type, with equal efficiency. Broad bearing surfaces, curved to conform with anatomical lines, serve to eliminate local pressure which often causes nerve irritation and interference with blood circulation. Prevention of overflow and leakage by means of horn 7 and a resilient pad placed

in groove 3, affords a degree of cleanliness most desirable, and in great measure lessens the labor of the attendant.

Having thus described my invention and set forth its features of novelty and utility, I claim as new and desire to obtain Letters Patent of the United States upon—

A bed pan of the character disclosed comprising a receptacle body substantially circular in form with a flat base; the rear, front and side walls being rolled upwardly and inwardly at varying heights from said base to form a pear shaped opening from above into said receptacle; the rear wall projecting upwardly to terminate in a horn with concave forward aspect, the edges of the same forming part of the boundaries of the

aforesaid opening; the forward end and side walls being turned sharply outward to form flanges or bearing surfaces of varying widths, said bearing surfaces forming a varying degree of incline upward from front to rear of said receptacle, adapted to conform to proper anatomical lines; the forward of said flanges being extended beyond the base of said receptacle body and provided with a transverse groove therein: a detachable apron adapted to provide an extension of said forward flange, and means of attaching said apron to said flange. 30

In testimony whereof I have signed my name to this application and power of attorney this 18th day of June, 1925.

MABEL E. NORTHRUP.
